US00D997709S

(12) **United States Design Patent** (10) **Patent No.:** **US D997,709 S**
Hancock (45) **Date of Patent:** **** Sep. 5, 2023**

(54) **PIN ASSIST DEVICE**(71) Applicant: **Truck Shields, LLC**, Salt Lake City, UT (US)2,400,960 A 5/1946 Strid
2,588,731 A 3/1952 Kabanuck
2,593,935 A 4/1952 Sweat

(Continued)

(72) Inventor: **Dennis H. Hancock**, Evanston, WY (US)

FOREIGN PATENT DOCUMENTS

(73) Assignee: **Truck Shields, LLC**, Salt Lake City, UT (US)CN 302787205 4/2014
DE 2710842 A1 9/1978

(Continued)

(**) Term: **15 Years**(21) Appl. No.: **29/815,773**

OTHER PUBLICATIONS

(22) Filed: **Nov. 16, 2021**Pin Whiz, Rhino Hitch website 2022, site visited Jul. 2, 2022,
https://rhinohitch.com/products/pin-wiz?variant=36191009570977&currency=USD&utm_medium=product . . .
(Continued)**Related U.S. Application Data**

(63) Continuation-in-part of application No. 17/132,808, filed on Dec. 23, 2020.

FIG. 1 is a front, right, top perspective view of a pin assist device showing my new design;

FIG. 2 is rear, right, bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings are for illustrative purposes only and form no part of the claimed design. The broken lines in the drawings depict portions of an environment of the pin assist device that form no part of the claimed design.

1 Claim, 5 Drawing Sheets# US D997,709 S
